UNITED STATES PATENT OFFICE.

LOUIS HEITZMANN, OF LONG ISLAND CITY, NEW YORK.

AUTOMATIC PLAYER PIANO.

Application filed December 26, 1924. Serial No. 758,194.

This invention relates to improvements in automatic player pianos of the pneumatic type and has for its primary object, the provision of a means for automatically locking 5 the key levers of the instrument when power is applied to the main bellows by means of the foot pedals or other power which may be employed, it being understood that when the key levers are unlocked, the instrument may 10 be played in the usual manner as that of an ordinary piano.

Another object of the invention resides in utilizing the vacuum set up by the main bellows for moving a lock bar to a locking 15 position and holding the same in this position until actuation of the foot pedals has ceased, whereupon the bar will automatically move to an unlocked position.

With these and other objects in view, the 20 invention resides in certain novel construction and combination and arrangement of parts, the essential features of which are hereinafter fully described, are particularly pointed out in the appended claims, and are 25 illustrated in the accompanying drawing, in which:—

Figure 1 is a detail transverse sectional view through a portion of a player piano showing my invention applied thereto and 30 with the lock bar in a non-locking position.

Figure 2 is a similar view but showing the lock bar in a locking position.

Figure 3 is a detail perspective view of a 35 portion of the key-board with the lock bar in locking position.

Figure 4 is a view showing a slightly modified form of my invention.

Referring more particularly to the drawing, the reference numeral 10 designates 40 the key board of a player piano, 11 the key levers pivoted by pins 12 in the usual manner, 13 the stickers operable by the key levers for operating the hammers, and 14 the main bellows operable respectively by 45 foot pedals 15. The main bellows 14 has communication with an air chamber or reservoir 16 through openings 17, and an air exhaust port 15' controlled by a flap valve 18.

50 A bellows 19 is suspended below the key-board and is connected with chamber 16 by a pipe or tube 20. A lock bar 21 extends the length of the key board beneath the key levers and is pivotally mounted as at 22.

55 An arm 23 is secured to the lock bar and is

connected with the movable wall of the bellows 19 by a connecting link 24. In the drawing, only one bellows 19, connecting rod 24 and an arm 23 is shown, but these parts may be duplicated at the other end of 60 the key board if desired for simultaneous operation.

In operation, we shall presume that the lock bar is in the position shown in Figure 1 of the drawing and pressure is applied to 65 either of the foot pedals 15 to depress the same. As the pedal moves forward the air in the bellows 14 is exhausted through the opening controlled by the flap valve 18 and only a small amount passes into the chamber 70 16. As the bellows moves backward to this former position by reason of the usual spring for returning the pedals to normal position, a suction or vacuum is created within the chamber 17 which in turn causes 75 the bellows 19 to collapse, thereby operating the link 24 which causes the arm 23 to move the lock bar to a position shown in Figure 2 of the drawing. When the lock bar is in this position, the key levers 11 are 80 locked against movement and will be held in this position by reason of the vacuum which is constantly maintained in the chamber 16 due to the successive operation of the foot 85 pedals. When pressure is relieved from both pedals, the pedals will assume an outward position which breaks the vacuum in the chamber thereby causing the bellows 19 to expand whereupon the lock bar is moved to a non-locking position. 90

In Figure 4 of the drawing, I have shown a slight modification of the locking means which includes a bellows 19' to which is connected one end of a link 25, the other end of the link having connection with an arm 95 26 of a pivoted member 27. The member 27 is formed with a locking extension 28 which is adapted to be moved into engagement with the ends of the key levers 11 when the bellows 19' is collapsed. The vacuum 100 for compressing the bellows 19' is similar to that shown in the preferred form and a description of the same is not deemed necessary. The member 27 extends the entire length of the key board for locking all of 105 the key levers simultaneously upon the collapsing of the bellows 19'.

From the foregoing description, it will be seen that I have shown and provided a mechanism which is automatically operable upon 110

the actuation of the foot pedals when it is desired to operate the piano as a player piano which eliminates the entire operation of certain devices now employed for this purpose. Although foot pedals have been shown for operating the main bellows, it will be appreciated that any other mechanism may be substituted therefor, such as an electric motor.

10 While I have described what I deem to be the most desirable embodiment of my invention, it is obvious that many of the details may be varied without in any way departing from the spirit of my invention, and 15 I therefore do not limit myself to the exact details of construction herein set forth nor

to anything less than the whole of my invention limited only by the appended claim.

What is claimed as new is:—

A pneumatically operated piano comprising a main bellows operated by a foot pedal, an auxiliary bellows connected therewith by a conduit, a link connecting the auxiliary bellows with a pivoted lock bar for the keys, a wind chest connected with the conduit having ports opening into the main bellows, and a flap valve in the main bellows to exhaust the air from the auxiliary bellows and operate the lock bar for the keys. 20 25

In testimony whereof I have affixed my signature.

LOUIS HEITZMANN.
